UNITED STATES PATENT OFFICE.

EDWARD E. JOHNSON, OF ST. PAUL, MINNESOTA.

WIRE GROOVING AND MILLING MACHINE.

1,141,713.

Specification of Letters Patent. Patented June 1, 1915.

Original application filed June 4, 1908, Serial No. 436,648. Divided and this application filed March 17, 1913. Serial No. 754,915.

To all whom it may concern:

Be it known that I, EDWARD E. JOHNSON, a citizen of the United States, resident of St. Paul, county of Ramsey, State of Minnesota, have invented certain new and useful Improvements in Wire Grooving and Milling Machines, of which the following is a specification.

The object of my invention is to provide a machine having means for grooving and milling a strand of wire which is subsequently coiled into a tube to form a well screen, this application being divided out of my pending application filed June 4, 1908, Serial No. 436,648, for tube forming machines.

The invention consists generally in various constructions and combinations, all as hereinafter described and particularly pointed out in the claims.

In the accompanying drawings forming part of this specification, Figure 1 is a plan view of a tube forming machine embodying my invention, Fig. 2 is a sectional view 25 through the frame and arbor of the milling mechanism, Fig. 3 is a front elevation of the milling mechanism, Fig. 4 is a detail sectional view of the milling guide, Fig. 5 is a sectional view on the line $y-y$ of Fig. 2, Fig. 6 is a sectional view, on the line $z-z$ of Fig. 2, Fig. 7 is a sectional view on the line $x-x$ of Fig. 2, Fig. 8 is a perspective view 30 of the wire before milling, Fig. 9 is a similar view, showing the wire after milling, Fig. 10 is a perspective view, showing a section of 35 the completed tube with the coils of the wire locked together.

In the drawing, 2 represents a suitable base, upon which the frame 3 of the machine 40 is mounted. The wire 4 is fed to the machine from a reel, not shown. The wire is obtained from wire-drawing mills, formed in cross section, substantially as illustrated in Fig. 8, and the first step in the operation 45 of the machine is to form a groove of the required depth, illustrated at the right hand of Fig. 9, and one that will be uniform throughout the entire length of the wire. To accomplish this I provide adjustable 50 guide rollers 5 and 6, between which the wire is inserted. A saw arbor 7 is journaled in a bracket 8 and provided with a suitable driving pulley 9. This pulley is driven independently of the other mechanism of the 55 machine by a belt 10, (see Fig. 2) to enable

the operator to start the saw and speed it up to the desired point before setting the rest of the mechanism in motion. I am also able to stop the machine and start it again without affecting the milling operation.

The arbor 7 has a device for end adjustment consisting, preferably, of a threaded thrust collar 11 and a loose thrust ring 12 for reducing the wear. A collet 13 is pinned on the arbor and has a recess in one end to receive the projecting end of a box 14 of said arbor. At its opposite end the collet has a broad bearing face 15 between which and a corresponding face 16 on a collet 17 the saw 18 is gripped and held. The faces of these collets are made as large as possible to support the saw close to the work, for as the groove is cut deeper on one side than on the other the saw would tend to bind unless supported laterally.

19 is a guide, (see Figs. 2 and 5) having a longitudinal groove 20 in its underside arranged to contact with and support the wire on the top, bottom and inner edge. Guide blocks 21 are provided, having holes 22 25 therein to receive pins 23, said holes being of sufficient size to permit lateral adjustment of said blocks by means of adjusting screws 24 mounted in the housing 25. These guide blocks support the outer edge of the wire and are held in close contact therewith by the adjusting screws. The guide 19 has an inclined rear face 26 and a wedge 27 is adapted to fit between said face and the wall of the housing 25 and has a threaded end secured by a sleeve nut in an arm 28. See Fig. 6. By adjusting the sleeve nut, the wedge may be moved lengthwise to release or clamp the guide. The guide is held against the wedge by means of adjusting 30 screws 29, (see Fig. 2). Transverse bars 30, fitting within recesses in the housing and the top of the guide, lock the latter against lengthwise movement. By means of the wedge and the adjusting screws, the guide 35 may be moved in or out to adjust the wire laterally with respect to the saw, and by means of the guide blocks 21, the tension of the wire as it is drawn through the guide can be regulated. The position of the guide is 40 varied vertically with respect to the saw arbor to accommodate it to saws of different diameter and to regulate the cut of the saw in making tubing of different sizes. This I 45 accomplish by making the housing 25 ver-

50 55 60 65 70 75 80 85 90 95 100 105 110

tically slidable on the bracket 8 in which the saw arbor is mounted. The housing and bracket are tongued and grooved together and held by a bolt 31 passing through holes of sufficient size in the housing to allow vertical adjustment by means of the adjusting screws 32. The outer collet 17 has an extension that is feathered on the arbor 7 and a collar 33 has an outwardly projecting lip 34 at its inner end and is threaded on the extension of the collet 17 so that endwise adjustment of the collar 33 is permitted, the collet 17 being locked against rotary movement by its feathered connection with the arbor.

15 A milling cutter 35 has an inwardly projecting lip 36 interlocking with the lip on the inner end of the collar 33 and a pin 37 is mounted in the collar 33 and arranged to project into a groove 38 in a cap 39 and in the end of the cutter, whereby the cap is locked against rotary movement and the collar is prevented from turning, except with the cap 39. This cap fits loosely on the collar and the outer end of the arbor is threaded and provided with a lock nut 40, which bears on the said cap and normally locks it against endwise movement. The milling cutter is provided with a series of milling teeth 41.

30 From the foregoing, it is evident that if the arbor 7 is held against rotation and the lock nut 40 is loosened, the cutter 35, the collar 33 and the cap 39 may be revolved as one piece and the threaded connection between the collar 33 and the collet 17 will cause endwise movement of the milling tool and adjust it with reference to the edge of the wire. When the lock nut 40 is tightened the collet 17 will be forced against the saw and through friction between the threads of the collet 17 and the collar 33 will lock the milling tool in position and against rotation with respect to the saw. The milling tool will also be forced against the lip at the inner end of the collar 33 and be locked against endwise movement with respect to the arbor. I am thus able, by means of one lock nut, to hold the saw and the milling tool in any desired relative position. It is important to do this, as I am thus able to regulate the amount cut off the edge of the wire by the cutter and determine the proper width of the groove formed between the coils of the wire in the completed tube. The width of this groove will vary with different conditions and may be made according to the needs of each particular case.

60 The housing incloses the outer portion of the arbor and extends back to the outer journal and permits the free discharge of the cuttings of the saw and the milling tool, and for the purpose of keeping the cutters cool and clean I prefer to provide a nozzle 65 41' arranged to direct a fluid through the

wall of the housing upon the cutting tool. The recessed end of the collet 13 inclosing the box 14 prevents any of the tool cuttings and liquid from working into the bearings. The cap 39 has a lip 42 formed thereon between which and the end of the milling tool an annular recess 43 is formed to collect the liquid from the tool and throw it off by centrifugal force within the housing. The opening in the wall of the housing through which the cap 39 extends must necessarily be of sufficient size to allow vertical adjustment of the housing. Consequently the lip and recess are necessary to prevent the liquid from flowing out on the cap and being thrown off therefrom upon the floor and other parts of the machine. A discharge opening 44 for the tool cuttings is provided, beneath which suitable receptacles, (not shown) may be arranged to receive the cuttings and return the liquid to the pump to be used over again.

I claim as my invention:

1. The combination, with a circular saw, of a guide arranged above the saw and having a groove in its under surface through which a wire is fed, the walls of said groove supporting the wire on the top, bottom and inner edge, and a milling device for the edge of the wire. 95

2. The combination, with a circular saw, of a guide having a groove to receive a wire and arranged to hold the face of the wire upon said saw, and a milling device mounted to operate upon one edge of the wire. 100

3. The combination, with a circular saw, of a guide having a groove above said saw and adapted to receive a wire and guide the same, a housing wherein said guide is mounted and means for adjusting said housing vertically to vary the position of the guide with respect to the saw and a milling device mounted to operate on the edge of the wire. 105

4. The combination, with a circular saw, of a guide having a groove therein to receive a wire, said guide having an inclined face on one side and a wedge device, and means for adjusting said wedge device lengthwise to move said guide laterally and change the position of said groove with respect to the saw and a revolving milling tool mounted to operate on the edge of the wire. 110

5. The combination, with a circular saw, of a guide through which the wire is fed past the saw, and means for regulating the tension thereon and a milling tool operating on the edge of the wire. 120

6. The combination, with a circular saw, of a wire guide and pressure blocks arranged to bear on a wire and hold its face in the path of the saw and regulate the tension thereon, and a milling tool mounted to operate on one edge of the wire. 125

7. The combination, with a saw, of a guide block adapted to receive a wire and direct 130

it over the saw, a housing wherein said guide block is mounted, pressure blocks arranged to engage one edge of the wire, and means for adjusting said pressure blocks to increase 5 or decrease their pressure on said wire and regulate the tension thereon and means for milling the edge of the wire.

8. The combination, with a saw arbor, of a collet secured on said arbor and having a 10 broad bearing face at one end, a second collet also mounted on said arbor and having a broad bearing face at one end, and a saw mounted on said arbor between said broad bearing faces and held securely thereby, said 15 bearing faces supporting the saw on each side thereof outwardly from the arbor to the bases of the teeth, and a guide through which a wire is adapted to be fed to said saw and means for milling one edge of the wire.

20 9. The combination, with a circular saw, of a wire guide having means for holding the under face of the wire upon the saw, and a revolving milling tool mounted to operate on the edge of the wire.

25 10. The combination, with a circular saw, of a wire guide having a groove therein to direct a wire past said saw, said saw cutting a longitudinal groove in the under side of said wire and a milling tool arranged to engage 30 gage the edge of said wire.

11. The combination, with a circular saw, of a guide having means for directing the face of a wire thereon, a milling tool mounted to engage the edge of the wire, and means 35 for adjusting said tool toward and from the wire.

12. The combination, with a circular saw, of a guide having means for holding a wire in the path of the saw, a milling tool arranged 40 to engage and trim the edge of the wire in said guide, a sleeve having means for moving said tool away from said wire, a cap inclosing said sleeve and adapted to move said tool toward said wire, said cap having a 45 feathered connection with said sleeve, whereby they will rotate simultaneously, and an arbor having a threaded end carrying a nut bearing on said cap.

13. The combination, with a saw arbor, of a circular saw secured thereon, collets mounted 50 on said arbor and between which said saw is held, one of said collets having an outer threaded end and feathered on said arbor, an interiorly threaded sleeve fitting the threaded end of said collet, an annular milling tool inclosing the inner portion of said threaded collet, said sleeve having means engaging said tool to move the same outwardly, a cap inclosing said sleeve and having a pin and groove connection therewith, 55 and means for adjusting said cap to move said milling tool inwardly, said sleeve turning on its collet simultaneously with said cap.

14. The combination, with a frame, of a 60 saw arbor, journaled therein, a saw mounted on said arbor, a housing carried by said frame and means for adjusting said housing vertically on said frame, and a guide block carried by said housing above said saw and 65 having a groove to receive a wire and direct it over said saw and a milling device for the edge of the wire.

15. A milling head comprising a guide block having a groove to receive the wire to 70 be milled, a milling tool operating to trim one edge of the wire in combination with a circular saw mounted to simultaneously operate on a face of the wire.

16. A milling head comprising a guide 80 block having a groove adapted to receive a wire fed lengthwise therein, means for tensioning the edge of the wire, a milling tool operating on an edge of the wire to trim the same, means for adjusting said tool toward 85 and from the wire, and a circular saw mounted to operate on the face of the wire simultaneously with the operation of said milling tool.

In witness whereof, I have hereunto set 90 my hand this 10th day of March, 1913.

EDWARD E. JOHNSON.
